UNITED STATES PATENT OFFICE.

COLL McDONALD, OF MORNINGTON, DUNEDIN, NEW ZEALAND.

CELLULAR CONSTRUCTION OF VESSELS.

1,366,269.

Specification of Letters Patent. Patented Jan. 18, 1921.

Application filed June 17, 1918. Serial No. 240,365.

To all whom it may concern:

Be it known that I, COLL McDONALD, a subject of the King of Great Britain, residing at Springhill Road, Mornington, 5 city of Dunedin, in the British Dominion of New Zealand, master mariner, have invented certain new and useful Improvements in Cellular Construction of Vessels, of which the following is a specification.

10 The present invention relates to cellular construction of vessels, rendering them less vulnerable against torpedo attack, collision, or grounding, and the object of the invention is to provide a system of water-tight 15 bulkheads, so arranging the holds, or compartments, that in the event of two or three holds, or compartments being flooded, the vessel will retain sufficient buoyancy to float.

20 With the above and other objects in view, which will hereinafter appear as the description continues, the invention consists of the novel features of construction, and formation of holds, or compartments, as 25 will be more fully described, and particularly pointed out in the appended claims.

Referring to the accompanying drawings wherein like and corresponding parts are designated by similar reference numbers 30 throughout the several views in which—

Figure 1 is a longitudinal section of a vessel, showing the method of arranging the holds, or compartments.

Fig. 2 is a plan of the vessel on the main, 35 or weather deck.

Fig. 3 is a plan of the vessel on the 'tween deck line.

The invention consists in dividing the hull of a vessel into a number of holds, or 40 compartments, such as 1. 2. 3. 4. 5. 6. 7. 8. 9. 10. 11. 12. 13. 14. 15., etc., as shown in Fig. 1, (the number of holds, or compartments, depending on the size, and design of the vessel) by an arrangement of water-tight bulkheads, 17. 18. 19. 20. 21. 22. 23. 45. 24. 25., these bulkheads extending from the bottom hull plating, or from the tank top to the hatch coamings, and by the thwartship bulkheads 30. 31. 32. 33. 34. 35., these 50 extending from the 'tween decks 16., to the top of hatches 26. 27. 27^A. 28. and 29.

The 'tween decks 16. extend from the fore peak bulkhead 36. to the thwartship bulkhead 20. and from the thwartship bulkhead 55 22. to the after bulkhead 37. having openings 38. for the discharge and loading of

cargo from the lower holds 2. 3. 5. 8. 9. 11. 13. and 15.

The space between the thwartship bulkheads 20. and 22. is (in this type of vessel) 60 reserved for the machinery and boilers, which may be isolated from each other by a water-tight bulkhead 21.

The hatches 26. give access to the lower holds 2. and 3. and the 'tween decks 1. 65 Access to the lower holds 2. and 3. is by way of the trunks 40. and 41.

The hatches 27. give access to the lower hold 5. and the 'tween decks 4. and 6. Access to the lower hold 5. is by way of the 70 trunk 42. between the 'tween deck compartments 4. and 6.

The hatches 28. give access to the lower holds 8. and 9. and 'tween deck compartments 7. Access to the lower holds 8. and 75 9. is by way of the trunks 43. and 44.

The hatches 29. give access to lower hold 11. and 'tween deck compartments 10. and 12. Access to the lower hold 11. is by way 80 of the trunk way 45.

The coamings 39. surround the hatches 26. 27. 27^A. 28. and 29. These hatches giving access to the different compartments.

This system of cellular construction can be adapted to any existing type of vessel, 85 and, in the construction of new vessels, this arrangement of multiplicity of compartments would result in only a slight increase in weight, and cost over the present method of construction.

90 By my arrangement of compartments, the liability of damage to the cargo by water, or fire, and the risk of the vessel's sinking, due to rupture by torpedo, mine, collision, or stranding, is reduced to a minimum. If 95 the hull plates in the lower holds 2. and 3. were ruptured, allowing both these compartments to be flooded, the 'tween deck compartments 1. 4. and 6. and lower hold 5. would give sufficient buoyancy to keep 100 the vessel floating. This also applies to the after holds or compartments of the vessel.

This system of construction adapts itself to vessels on long voyages, carrying cargo for different ports, which can be so stowed 105 that on discharge at the different ports, the trim and stability of the vessel is not impaired.

My system of cellular construction is applicable to sailing vessels, as well as steam- 100 ers.

I am aware that the subdivision of ves-

sels by means of water-tight bulkheads is not new, but I am not aware that such an arrangement of water-tight bulkheads as I have invented has been used in shipbuilding construction before.

Having thus fully described my invention, what I claim as new and desire to secure by Letters Patent is:

1. A vessel having a hatch, a horizontal 10 water-tight deck dividing said vessel into upper and lower compartments, and vertical water-tight bulk heads sub-dividing said upper and lower compartments, said bulk heads forming a plurality of water-tight 15 trunk ways extending from said lower compartment to said hatch to afford access to the former from the latter, substantially as described.
2. A vessel having a hatch, a horizontal 20 water-tight deck dividing said vessel into upper and lower compartments, and vertical water-tight bulk heads subdividing said compartments, said bulk heads forming a plurality of water-tight trunk ways extending 25 from said lower compartment to said hatch to afford access to the former from the latter, certain of said bulk heads extending to the bottom of said lower compartment, substantially as described.
3. A vessel having a hatch, a horizontal 30 water-tight deck dividing said vessel into upper and lower compartments, and vertical water-tight bulk heads subdividing said upper and lower compartments, said bulk 35 heads dividing said hatch and forming a plurality of water-tight trunk ways extending from said lower compartment to said hatch to afford access to the former from the latter, substantially as described.
4. A vessel having a plurality of hatches 40 and a horizontal water-tight deck and vertical water-tight bulk heads dividing said

vessel into an upper and a lower series of 45 water-tight compartments, each of the compartments of said upper series communicating with one of said hatches, certain of said bulk heads extending from said hatches to said horizontal deck and other of said bulk heads extending from said hatches to the bottoms of said lower compartments, said bulk heads forming water-tight trunk ways 50 each separately affording access to one of said lower compartments from one of said hatches, substantially as described.

5. A vessel having a hatch, a horizontal 55 water-tight deck dividing said vessel into upper and lower compartments, vertical water-tight bulk heads for subdividing said upper compartment, and a vertical water-tight bulk head of greater extent than the 60 first named bulk-heads interposed therebetween for subdividing said lower compartment and forming trunk ways whereby a plurality of lower subdivisions and a single 65 upper subdivision are accessible from said hatch.

6. A vessel having a hatch, a horizontal water-tight deck dividing said vessel into upper and lower compartments, a vertical water-tight bulk-head for subdividing said 70 upper compartment and a vertical water-tight bulk-head of greater extent than the first named bulk-head for subdividing said upper and lower compartments and forming trunk ways whereby a plurality of upper 75 subdivisions and a single lower subdivision are accessible from said hatch.

In testimony whereof, I affix my signature, in presence of two witnesses.

COLL McDONALD.
